(57) **CLAIM**

The ornamental design for a combined night light with digital clock, as shown and described.

DESCRIPTION

FIG. 1 is a front and top perspective view of a combined night light with digital clock, showing my new design; FIG. 2 is a rear and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and, FIG. 9 is an enlarged view of a portion labeled, 'FIG. 9' in FIG. 2.

The broken lines in the figures illustrate portions of the combined night light with digital clock that form no part of the claimed design. The dash dot dash lines in FIGS. 2 and 9 are for the purpose of depicting the cut line of the enlarged view and form no part of the claim.
